PRESS OPERATING MECHANISM

James M. Dewey, Cincinnati, Ohio, assignor to
The American Laundry Machinery Company,
Norwood, Ohio, a corporation of Ohio

Application June 12, 1935, Serial No. 26,119

4 Claims. (Cl. 38—25)

This invention relates to a pressing machine of the type used in laundry and garment work and to an improved control mechanism therefor.

My invention provides a pair of coacting pressing members, each movable toward the other, one of the members being preliminarily movable into position adjacent the other and thereafter the other member is moved into final heavy pressure engagement therewith. Power means is provided for the preliminary movement of the one member, the power means acting with low power during the first portion of the preliminary movement and with high power during the latter portion of said movement.

15 My improved pressing machine provides in a pressing machine of the type just described a cylinder and piston motor of relatively small diameter and long stroke for preliminarily moving one of the pressing members into its final position, the motor being connected with its associated pressing member by two different motion transmitting mechanisms. One of these motion transmitting mechanisms is effective during the early part of the motor stroke to position the pressing member in its final position and is of 20 low power. The other motion transmitting mechanism is effective during the latter part of the motor stroke and is of high power and sufficient to resist the final pressure between the pressing members.

25 Another feature of my invention is the provision of a pressing machine, one of whose pressing members comprises a flexible, distensible and fluid-impervious member underlying the pressing surface thereof and distensible to cause final pressure engagement between the pressing members. Combined with this type of pressing member I provide a coacting member with low power means for moving the coacting member into position adjacent the distensible member and high power means for holding the coacting member in that position while the distensible member applies final pressure against it.

30 My improved control mechanism provides a pressing machine of the type described in which the movement of the pressing members into final pressure engagement is automatically initiated after the high power mechanism effectively holds the coacting member in its final position.

35 Other features of my invention include spaced safety manuals for controlling the preliminary movement of the pressing members into position adjacent each other, means for maintaining the two-hand controls in actuated position while final pressure is applied, and novel means for

automatically initiating the application of final pressure.

In the drawings, Fig. 1 is a view partly in elevation and partly in section of a pressing machine embodying my invention, with the pressing members in open position and showing the control mechanism diagrammatically; while Fig. 2 is a similar view showing the pressing members in closed position.

40 The drawings illustrate a pressing machine 10 comprising a frame 10 upon which is mounted a pressing bed 11 with which a pressing head 12 coacts. The pressing head is carried by a head lever 13 pivotally mounted intermediate its ends at 14 on a frame bracket 10a. The pressing members shown are particularly adapted for pressing articles such as men's shirts wherein the sides of the shirt or portions thereof may be ironed by the depending side portions 12a of the head coacting with suitable portions of the bed, but my invention is applicable to other types of pressing members, as will be readily understood. Means, not shown, may be provided for heating one or both of the pressing members as desired.

45 Means is provided for moving the pressing head into its final position adjacent the pressing bed. This means comprises a power means connected with the head lever by two motion transmitting mechanisms, one of greater mechanical advantage than the other, the connection of lesser mechanical advantage being utilized during the first portion of the head movement from open toward its final position and the high power mechanism becoming effective during the latter portion of the head movement.

50 It results from this arrangement that a cylinder and piston motor 15 may be utilized of a relatively small diameter and relatively long stroke, the motor having sufficient power during the early part of its stroke to move the head almost into its final position but which, without other provision, would be insufficient to hold the head in its final position when pressure is applied through the bed.

55 However, toward the end of the stroke of the motor 15 a leverage of greater mechanical advantage becomes effective which is sufficient to hold the head in place during the final pressing action. The mechanism shown comprises a cylinder 15a in which reciprocates a piston 15b whose piston rod 15c is pivotally connected at 16 with the longer arm 17a of a bellcrank 17 which is pivotally mounted on the rear end of the head lever at 18. The shorter arm 17b of the bellcrank carries a follower 19 which

cooperates with a cam 20 on a portion of the frame 10. This cam 20 has a portion 20a and a portion 20b, the action of which will be later described. A tension spring 21 is connected between a portion of lever 13 and bellcrank lever 17 to bias the bellcrank in a clockwise direction. A spring 22 connected between the rear end of the head lever and a portion of the frame biases the pressing head toward its open position. Springs 23 and 24 cushion the movement of piston 15b at the opposite ends of its stroke.

The fluid supply for motor 15 is by way of conduit 25, valve casings 26 and 27, and conduits 28 and 29. Valve casing 26 houses a normally closed inlet valve 26a and a normally open outlet valve 26b mounted on a common stem 26c and actuatable by manual 26d. A spring 26e biases the valves toward their normal position and a servo motor 26f when energized holds the valves in their operated position. Valve casing 27 houses a normally open outlet valve 27a on a stem 27b and actuatable by a manual 27c. A spring 27d biases this valve toward its normal position and a servo motor 27e when energized holds the valve in its operated position. Manuals 26d and 27c are so spaced as to require the use of two hands of an operator to actuate them and both must be actuated simultaneously to energize motor 15 as will presently appear. Means is provided for holding the valves in casings 26 and 27 in their operated position upon movement of the head into its final position adjacent the bed. The means shown comprises a port 30 in cylinder 15a which is uncovered by piston 15b as it reaches the end of its stroke. A conduit 31 has branches 31a and 31b which conduct pressure fluid from port 30 to servo motors 26f and 27e to hold the valves in operated position after piston 15b has passed port 30 on its power stroke.

Various means might be utilized for causing final pressure engagement between the pressing members, but in the form shown the pressing bed 11 comprises a supporting member 11a and in spaced relation therewith a flexible, distensible and substantially fluid-impervious cover member 11b which underlies substantially the entire pressing surface of the bed and is secured at its edges in fluid-tight relation to the member 11a as, for instance, by suitable strips 11c. It is understood that the member 11b might contact an article to be processed either directly or through suitable padding, as desired. The fluid supply to the space 11d beneath the cover member is by way of conduit 35 through which a flow of pressure fluid is initiated automatically upon the pressing head reaching its final position as will be next described.

Means is provided for automatically raising the pressing surface of the bed into pressure engagement with the head when the latter has reached its final position, that is to say, when the high power mechanism has become effective to hold the head in its final position. The means shown comprises a device rendered effective during the latter portion of the stroke of piston 15b and in the present instance the port 30 is utilized for this second function in addition to the maintaining function just described. The device for thus initiating movement of the bed pressing member comprises a valve casing 32 which is similar to valve casing 26 and the parts have been similarly designated. However, in the construction shown in casing 32 no manual has been provided for operation of this device but instead a lever 33 transmits motion of servo motor 32f

to valve stem 32c to actuate the valves to their "on" position. The valves in casing 32 are supplied with motive fluid by conduit 34 connected with conduit 25 or other suitable source of power. Usually a reducing valve 34a will be provided in conduit 34 to reduce the pressure of the fluid supplied to the inflatable cover member. Servo motor 32f is energized by the conduit connection 31c with conduit 31 after piston 15b has opened port 30.

With the parts in the position of Fig. 1, the operation of the mechanism is as follows: The operator places an article in position upon the pressing bed and actuates the manuals 26d and 27c to the position shown in Fig. 2. Pressure fluid flows through conduit 25, valve casing 26 and conduits 28 and 29 to cylinder 15a. At this time valve 21a must be held in its operated position or fluid will escape without effect upon motor 15. During the first portion of power stroke of piston 15b, power is applied at the point 16 and has a tendency to rotate the bellcrank 17 in a counterclockwise direction. However, such rotation of the bellcrank is resisted by the engagement of follower 19 against the cam portion 20a. Bellcrank 17 and head lever 13 therefore move as a unit about the pivot 14, the leverage applied at this time being that due to the lever arm between the points 14 and 16. This continues until the head 12 has nearly reached its final position at which time follower 19 passes the heel of cam 20 so that the follower engages the cam portion 20b. The follower 19 now becomes the fulcrum for bellcrank 17 and the final movement of piston 15b applies a powerful leverage to the head lever at the point 18. This moves the pressing head and its associated parts to the position of Fig. 2. As piston 15b passed the port 30, motive fluid passed therethrough and by way of conduits 31 and 31c to servo motor 32f actuating the valves in casing 32 to their "on" position as shown in Fig. 2, thus permitting a flow of pressure fluid through conduits 25 and 34, valve casing 32 and conduit 35 to the space 11d beneath the cover member 11b, raising the pressing surface of the bed into pressure engagement with the head. When motive fluid was supplied to conduit 31 through port 30, pressure was applied through conduits 31a and 31b to the servo motors 26f and 27e to hold the valves in casings 26 and 27 in their operated positions.

To open the press, the operator moves manual 26d or 27c or both, against the action of the respective servo motors which will exhaust motive fluid through valve 26b or valve 27a or both. This evacuates cylinder 15a, as the result of which spring 21 first becomes effective to cause a clockwise movement of bellcrank 17 with respect to head lever 13 and when follower 19 has passed from cam portion 20b to cam portion 20a, spring 22 becomes effective to rotate the head lever in counterclockwise direction until the parts come to rest in the position of Fig. 1. The first release of pressure fluid through valve 26b or valve 27a reduces the holding effect in motor 32f and permits spring 32e to start valves 32a and 32b toward their "off" position, thus partly relieving the pressure beneath cover member 11b. Means is provided for the evacuation of fluid from the left-hand end of cylinder 15a preferably by providing a leak port 15d in the rear end of cylinder 15a. Therefore, as soon as piston 15b has passed port 30 on its return stroke, servo motor 32f is completely exhausted and spring 32e returns valves 32a and 32b to the position of Fig. 1.

which cuts off the supply of motive fluid to the bed. This occurs before the head has retreated an appreciable distance from the bed. It results from this arrangement that pressure fluid is supplied beneath the cover member 11b in effective amounts only when the pressing head is in position to limit the amount of cover distension so that the cover member is not ruptured.

My improved construction thus supplies a yielding fluid pressure cushion for holding the head in its final position while pressure is applied by way of the bed. Also, the motor 15 may be so constructed that while its power is sufficient through the first acting leverage acting on the 15 arm represented by the distance between points 14 and 16, to move the head into its final position, it would be insufficient to hold the head there against the pressure exerted by the bed. However, the second acting leverage exerted about the 20 fulcrum between follower 19 and cam portion 20b is sufficient to resist the final pressure. It results from this construction that I am able to make satisfactory use of a cylinder and piston motor of relatively low power.

25 What I claim is:

1. In a pressing machine, a frame, a head lever carried thereby, a pressing head movable by said lever from open to final position, a pressing bed including a flexible distensible cover member for 30 moving substantially the entire pressing surface of said bed into engagement with said head when the latter is in its final position, a cylinder and piston motor having operative connections with said head lever of two different leverages, said 35 connections including low- and high-power leverages effective respectively during early and late portions of said piston stroke, said motor acting through said low-power leverage being insufficient to resist pressure engagement of said 40 bed against said head, fluid supply means for said motor, control means therefor, fluid actuated maintaining means for holding said control means in operated position, and means for simultaneously supplying fluid to said maintaining means and 45 to said cover member to distend the same after said high power leverage becomes effective.

2. In a pressing machine, a frame, a head lever carried thereby, a pressing head movable by said lever from open to final position, a pressing bed 50 including a flexible distensible cover member for

moving substantially the entire pressing surface of said bed into engagement with said head when the latter is in its final position, a cylinder and piston motor having operative connections with said head lever for moving said head into final 5 position, fluid supply means for said motor, control means therefor, fluid actuated maintaining means for holding said control means in operated position, fluid supply means for distending said cover member including a fluid actuated control 10 device, a port in said cylinder adapted to be opened by said piston upon reaching that portion of its stroke wherein said head is placed in final position, and an open conduit connecting said port with said control device and with said 15 maintaining means.

3. In a pressing machine, a pair of coacting pressing members each movable toward the other, a cylinder and piston motor for moving one of said members from open position to final position and for holding it there, fluid supply means for said motor, control means for said fluid supply means, fluid actuated maintaining means for holding said control means in operated position, fluid pressure actuated means for moving said 25 other member into pressure engagement with said one member, a port in said cylinder adapted to be uncovered upon predetermined movement of said piston, and an open conduit connecting said port with said maintaining means and with said fluid 30 pressure actuated means.

4. In a pressing machine, a pair of coacting pressing members each movable toward the other, a cylinder and piston motor for moving one of said members from open position to final position 35 and for holding it there, fluid supply means for said motor, control means for said fluid supply means, fluid actuated maintaining means for holding said control means in operated position, a flexible distensible and substantially fluid-im- 40 pervious cover member for raising the entire pressing surface of said other member into engagement with said one member, a fluid supply for said cover member, a fluid pressure actuated control device for said fluid supply, a port in said 45 cylinder adapted to be uncovered upon movement of said one member into final position, and an open conduit connecting said port with said control device and with said maintaining means.

JAMES M. DEWEY. 50
